CLAIM

The ornamental design for an elevated floor plate, as shown and described.

DESCRIPTION

FIG. I is a top perspective view of an elevated floor plate showing our new design;

FIG. II is an enlarged bottom plan view thereof;

FIG. III is a sectional view taken along line III—III of FIG. II;

FIG. IV is a top plan view of a modified form of the elevated floor plate shown in FIG. I;

FIG. V is a bottom plan view thereof; and,

FIG. VI is sectional view thereof taken along line VI—VI of FIG. IV.
